SHOE SHINE KIT

Robert B. Karoff, New York, N. Y., assignor to Karoff Originals, Ltd., New York, N. Y., a corporation of New York

Application May 11, 1955, Serial No. 35,910

Term of patent 14 years

(Cl. D9—2)

FIG. 1.

FIG. 2.

Fig. 1 is a front perspective view of a shoe shine kit in closed position, showing my new design; and

Fig. 2 is a side perspective view of the same in open position.

I claim:

The ornamental design for a shoe shine kit, as shown.
